TOP ROLL CLEAVER FOR DRAWING FRAMES

Charles D. Miller and L S Lyles, Chester, S. C.

Application October 24, 1947, Serial No. 781,882

3 Claims. (Cl. 19—139)

1

This invention relates to means for scavenging or removing loose fibres, lint and the like from textile rolls, in drawing frames, spinning frames and the like.

It is a well known fact that in the drafting of textile fibres, such as in roving frames, drawing frames, spinning frames and the like, loose fibres are accustomed to collect into bunches on the front rolls and cause the front rolls to eye-brow and then these bunches of fibres or lint will be cast off by the front rolls and carried along by the roving or strand being processed, thus resulting in slubs, clots, and large places in the yarn and the like.

It is an object of this invention to provide a clearing mechanism for the top rolls of drawing frames and the like for removing loose fibres therefrom and which clearing mechanism is adapted to be moved back and forth, forwardly and rearwardly relative to the top rolls, by means driven by the machine.

It is another object of this invention to provide clearing means for textile drawing rolls and the like which will not only contact the top rolls and remove lint and other loose fibres therefrom, but which will reciprocate backwardly and forwardly, with relation to the top rolls, to thus provide a very much better cleaning action than would be the case if the contacting means were stationary with relation to the rolls.

Some of the objects of the invention having been stated, other objects will appear as the description proceeds when taken in connection with the accompanying drawings, in which

Figure 1 is a front elevation of a section of a drawing frame and showing the clearer board in raised position;

Figure 2 is a top plan view of a section of a drawing frame and showing the central portion of the cover above the clearer board broken away in order to illustrate the invention;

Figure 3 is a transverse sectional view taken along the line 3—3 in Figure 2 and showing the clearer board in almost fully advanced position;

Figure 4 is a view similar to Figure 3 but showing the clearer board almost in its most rearward position.

Referring more specifically to the drawings, the numeral 10 indicates suitable bearing stands secured on a suitable support such as a board 11. Secured on the upper surfaces of these stands 10 by any suitable means such as bolts 12 penetrating slots 13 are the rear bearings 14 and intermediate bearings 15 and 16 and front bear-

2

ings 17. In each of these is mounted a roller neck 18 which is usually supported within a suitable sleeve 19. These roller necks are secured in any suitable manner such as by threading into the ends of the bottom fluted rolls 20, 21, 22 and 23 reading from the rear to the front of the drawing frame.

These bottom rolls are driven from any suitable means at the end of the machine, which is 10 not shown. Resting on top of the sleeves 19 are the fixed sleeve members 25 which are flattened on their sides as at 26 to fit into the slots 27 of the bearings 14 to 17 inclusive, and in these sleeves 25 are rotatably mounted the end bearing portions 30 of the top rolls 31 which usually have a rubber, leather or cork covering 32. Suitable pressure applying means are applied to the top rolls to hold them in contact with the fluted bottom rolls but such pressure applying 20 means is not shown, but these pressure applying means are usually hooked into the peripheral grooves 33 in the sleeves 25.

Slivers are adapted to pass between the top and bottom rear rolls and forwardly and out 25 from between the top and bottom rolls. It often happens that lint is picked up by the top rolls and the lint is collected on the top rolls into slubs or bunches and later are transferred back into the sliver or roving passing between the top and bottom rolls. Some means must be provided 30 for properly cleaning these top rolls and preventing the bunches of lint and loose fibres from being carried around by the top rolls and deposited into the roving or sliver passing between the top and bottom rolls.

The supports 10 have secured thereto, by any suitable means such as a screw 40, uprising brackets 41 in which is oscillatably mounted a shaft 42. Also oscillatably mounted on the shaft 42 are bearing portions 43 which are integral with a steel or cast cover 44 which covers the top rolls, and the downwardly projecting wall portion 45 of the cover 44 is adapted to rest on top of the front bearings 17 to limit downward 45 movement of the cover 44.

Thus the cover 44 is pivoted on the shaft 42 and can be moved from the position shown in Figures 3 and 4 to an elevated position shown in Figure 1.

50 The lower surface of the horizontal portion of cover 44 has projecting downwardly therefrom a pair of spaced pins 50 and 51 which project through suitable slots 52 and 53 in plates 54 and 55 secured on top of a board 56. The lower ends 55 of these pins 50 and 51 are internally threaded

into which are driven screws 58 having a washer 59 therearound to limit downward movement of the plates 54 and 55 relative to the pins 50 and 51. By this arrangement the downward movement of the board 56 is limited and the slots 52 and 53 allow back and forth reciprocatory movement of the board 56. This board 56 is covered with a felt cloth 60 on its lower surface, which extends up and covers the front and rear edges of the board and is secured on the top portions of the board 56. This felt is adapted to rest on the top roller coverings 32 by the weight of the board itself.

In order to impart reciprocatory back and forth movement to the board 56, there are secured in each end of the board screws 65 and 66 to which are pivoted arms 67 and 68 which extend rearwardly and are pivoted as at 69 and 70 to the upper ends of arms 71 and 72 which are fixedly secured at their lower ends on the shaft 42. There is also fixedly secured on the shaft 42 an arm 75 to the lower end of which is pivotally secured as at 76 a connecting rod 77 which is pivotally secured as at 78 on a pinion 79 in an off-center position. The pinion 79 is mounted on a stub shaft 80 fixed in a bracket 81 secured on a board 82 which is supported by brackets 83 secured to the brackets 41 as at 85. The board 82 is held in position on the arms 83 by means of bolts 87.

The pinion 79 meshes with a pinion 90 fixed on a rotatable shaft 91 mounted in a suitable bearing 92 and driven from the head portion of the machine by conventional means not shown.

It is thus seen that as the machine operates, and as slivers or roving are being passed through the sections of the drawing frames, that is between the top and bottom rolls, the shaft 91 will also be rotated, and this will impart reciprocatory back and forth motion to the board 56 to move it forwardly and rearwardly to thus wipe the lint and other fibres collected on the rolls and especially the top front roll to thus prevent its eye-browsing and casting off bunches of fibres into the yarn to form slubs and other imperfections.

In the drawings and specification there has been set forth a preferred embodiment of the invention, and although specific terms are employed, they are used in a generic and descriptive sense only, and not for purposes of limitation, the scope of the invention being defined in the claims.

We claim:

1. In a drawing frame and the like having top and bottom rolls, a cover disposed above the top rolls, an oscillatable shaft at the rear of the frame on which the rear edge of the cover is pivoted, a pair of downwardly projecting pins extending from the lower surface of the cover, a board disposed between the pins and having a plate secured to and extending from each end thereof, each of the plates being slotted in a direction transverse to the axes of the rolls and through which the pins are adapted to project, means on the lower ends of the pins for supporting the board when the free end of the cover is raised, said board having a felt covering on its lower surface for contacting the top rolls, and means

connecting the board and the oscillatable shaft for imparting reciprocatory movement to the board in a direction which is transverse to the longitudinal axes of the rolls.

2. In a drawing frame and the like having top and bottom rolls, a cover disposed above the top rolls, an oscillatable shaft at the rear of the frame on which the rear edge of the cover is pivoted, a pair of downwardly projecting pins extending from the lower surface of the cover, a board disposed between the pins and having a plate secured to and extending from each end thereof, each of the plates being slotted in a direction transverse to the axes of the rolls and through which the pins are adapted to project, means on the lower ends of the pins for supporting the board when the free end of the cover is raised, said board having a felt covering on its lower surface for contacting the top rolls, a pair of arms fixed on the oscillatable shaft, a connecting rod between the free end of each arm and an end of said board for imparting oscillatory movement to the board in a direction which is transverse to the axes of the top rolls.

3. In a drawing frame and the like having top and bottom rolls, a cover disposed above the top rolls, an oscillatable shaft at the rear of the frame on which the rear edge of the cover is pivoted, a pair of downwardly projecting pins extending from the lower surface of the cover, a board disposed between the pins and having a plate secured to and extending from each end thereof, each of the plates being slotted in a direction transverse to the axes of the rolls and through which the pins are adapted to project, means on the lower ends of the pins for supporting the board when the free end of the cover is raised, said board having a felt covering on its lower surface for contacting the top rolls, a pair of arms fixed on the oscillatable shaft, a connecting rod between the free end of each arm and an end of said board for imparting oscillatory movement to the board in a direction which is transverse to the axes of the top rolls, means for driving the oscillatable shaft comprising a driven shaft, a pinion on said driven shaft, an eccentrically mounted crank pin fixed on one side to the pinion, a lever arm fixed to the oscillatable shaft and a connecting link extending between and pivotally connected to the eccentrically mounted crank pin and to said lever arm.
